STOKER FUEL DISTRIBUTOR

George M. Broker, Erie, Pa., assignor to The Standard Stoker Company, Incorporated, a corporation of Delaware

Application December 3, 1936, Serial No. 113,968

4 Claims. (Cl. 110—104)

This invention relates to stokers and more particularly to improved means in a stoker for deflecting fuel into the zone of action of the distributing means.

5 It is an object of this invention to provide in a stoker, a deflector that is easily and readily adjustable and capable of deflecting fuel to the fuel distributor in proper amounts without interfering with the free passage of fuel toward the fuel distributor.

10 A further object of this invention resides in the provision of a pivoted deflector of the above construction, the pivot point of which is directly above the pressure fluid device.

15 It is also an object of this invention to provide a pivoted fuel deflector which is provided on its under side, and at the foremost edge thereof, with an enlarged portion for diverting laterally, irrespective of the angular position of the deflector, 20 a certain amount of the preponderant mass of fuel passing through the stoker conduit to the fuel distributor.

With these and other objects in view, which will become apparent as the description proceeds, 25 the invention resides in the construction, combination and arrangement of parts, hereinafter more fully described and illustrated in the accompanying drawing, in which—

Figure 1 is a central vertical sectional view 30 through the rearward portion of a locomotive and the stoker thereof, showing the invention partly in similar section and partly in side elevation;

Figure 2 is a plan view of the stoker structure illustrated in Figure 1 with portions of the locomotive in section; and

35 Figures 3 and 4 are sectional views taken on the lines 3—3 and 4—4, respectively, of Figure 1.

In the drawing, 10 designates a boiler firebox of conventional design having a backhead 11 with a firing opening 12, and provided with the grate 13. Fuel is delivered to the firebox by suitable stoker mechanism, only so much being shown as is necessary to a complete understanding of this invention.

40 The forward tubular conduit section or riser of a flexible conduit system extending from a source of fuel supply, as the bin of a locomotive tender, to the firing opening 12 of the boiler is designated as 14. The riser 14 is carried on the backhead 11 by a supporting bracket 15. The riser terminates at its lower end in a spherical seat 16 receiving the ball member 17 of a conduit section 18 leading forwardly from a source of fuel supply.

45 From its lower end the riser extends upwardly

and forwardly, flaring outwardly at its upper end, and communicates with the firing opening 12 through its laterally spreading and substantially horizontal mouth portion 19. The mouth portion 19 is provided with the flanges 20, 20a for attachment to the backhead by suitable fastening means, as by bolts. This mouth portion is formed with an upstanding wall 21 to which is detachably secured a distributor plate 22, which plate forms an extended floor portion of the riser projecting through the firing opening 12 of the backhead.

5 The riser 14 is provided with an upwardly directed opening 23 which is closed by a cover 24. Bolts 25 are utilized for detachably securing the cover to the riser 14. Between its side portions 24a, 24b, the cover 24 is provided with a recess 26 extending from the lower rearward edge of the cover 24 to a point rearward of the firedoor 27. Within the recess 26 a supplemental cover 28 is 10 positioned, the supplemental cover 28 being hinged to the upper end of the cover 24 as at 15 29. Clamps 30 securely fasten the supplemental cover 28 in position.

20 Rearwardly of the distributor plate 22 and outside the firebox is a vertically disposed nozzle or distributor head 31 to which pressure fluid such as steam is supplied by a desired number of supply pipes 32. The head 31 is provided with openings 33 in horizontal alignment for emitting a fan-shaped blast of pressure fluid across the distributor plate 22. Disposed in the conduit section 18 is a screw 34, preferably formed with an additional flight 34a at its forward end to assist in insuring a continuous delivery of fuel onto the distributor plate 22.

25 In stoking devices of the character described and illustrated in the drawing, it has been found, in practice, that the screw conveying means has a tendency to discharge more fuel to one side of the riser than to the other and as a consequence, the fuel stream delivered into the zone of action of the steam blasts is of unequal volume; thereby more fuel is spread over one side of the firebox than the other, establishing troublesome fire conditions. The side toward which the greater amount of fuel is delivered depends upon the direction of rotation of the screw while advancing the fuel forwardly.

30 This invention provides novel means to overcome this uneven delivery and distribution of fuel comprising a deflector vane 35 which is carried by the supplemental cover 28. The deflector vane 35 is somewhat triangular in shape, consisting of a bottom edge 36 disposed wholly above 35

the jet head 31, the front edge 37, and a rear edge 38 which is curved in conformity to the inner shape of the supplemental cover 28. The front edge 37 of the deflector vane is disposed 5 mainly in the transverse vertical plane of the front face of the distributor head 31 while the bottom edge 36 is disposed above the plane of the head 31 and is V-shaped in transverse vertical cross section. The apex of the V-shaped 10 bottom edge 36 is directed downwardly toward the column of fuel being elevated through the riser 14 and is effective to split and divide the on-coming single column of fuel into two columns, each being of greater or lesser volume depend- 15 ing upon the position of the deflector vane 35.

In order to permit angular adjustment of the deflector vane 35, the upper forward end thereof is provided with a shaft portion 39, the axis of which is disposed centrally of the riser 14 and 20 lies in the transverse vertical plane passing a slight distance rearward of the distributor head front face. The shaft portion 39 of the deflector vane 35 is journaled in a bearing 40 formed in the foremost edge of the supplemental cover 28. 25 Above the shaft portion 39 is a square extension 41 over which is passed and engaged in operative relation the handle 42. A pin 43 is driven through both the extension 41 and the handle 42, thereby firmly securing the handle in operative 30 relation with the deflector vane 35.

From the square extension 41, the handle 42 extends rearwardly and downwardly, terminating in a lug 44 which seats upon a flange 45 extending rearwardly from the supplemental cover 28. 35 This flange 45 is provided with an arcuate slot 46 constituting a raceway for the bolt 47. The bolt 47 on its under side is provided with a head 48 and on its upper side has a threaded portion 49 arranged to be engaged by a hand nut 50. When 40 the nut 50 is loosened, the handle 42 and deflector vane 35 may be moved to a desired position. Tightening of the nut 50 draws the head 48 of the bolt 47 against the under side of the flange 45, thereby firmly securing the handle 42 and deflec- 45 tor vane 35 in the desired position.

The fuel deflector vane 35 is provided in its lower foremost portion with an enlargement or bulb 51, the foremost edge of which extends forwardly beyond the jet head 21 while its sides 51a, 51b merge into the plate-like portion of the deflector vane 35. The function of this enlargement 50 51 is to cause the preponderant amount of fuel within the central portion of the mouth portion 19 to be more equally proportioned laterally.

If banks of fuel are formed on the left or right side of the firebox, they can be burned away and the fire leveled out by so adjusting the deflector vane 35 as to starve the banked side and feed 60 more fuel to the opposite side. Thus, if it is desired to starve the left side of the firebox, the deflector vane 35 is moved so that its lower rearward edge is nearer the left side of the riser 14. The closer the lower rearward edge of the 65 deflector vane 35 is to the left side of the riser, the less fuel will be fed to the left side of the firebox. Similarly, banks may be removed from the right side of the firebox. Should a bank 70 occur in the central portion of the firebox, the deflector vane 35 may be maintained in its central position, and, by reducing the pressure of fluid issuing from the central group of jet openings 33, the bank will be reduced. It should be particularly noted that, regardless of the 75 angular position of the deflector vane 35, the

enlargement 51 always remains in a position to cause a lateral spreading of the preponderant amount of fuel in the central portion of the discharge mouth 19.

The deflector vane constructed according to 5 this invention has been found to be effective in controlling the quantities of fuel fed into the zone of action of the distributor system, such control of fuel being accomplished without appreciable interference to the passage of fuel 10 through the riser conduit.

I claim:

1. In a furnace having a wall with a firing opening therein, a stoker for feeding fuel to said furnace comprising a riser conduit having 15 an upwardly extending portion and a forwardly directed discharge mouth in communication with said firing opening, means below the level of said discharge mouth for urging fuel upwardly through said riser conduit in a core shaped mass, 20 distributing means at the discharge mouth of said riser conduit including a distributor plate and a distributor jet head at the rear of said distributor plate, said jet head having a front face provided with a plurality of jet openings 25 for emitting blasts of pressure fluid over said distributor plate, and a fuel deflector vane associated with said distributing means and arranged to act on the fuel prior to the action thereon of the pressure fluid blasts issuing from said 30 jet head, the said deflector vane being pivotally mounted at substantially its forward end for movement about an upright axis, said vane being disposed in said conduit with its pivotal axis lying in a plane extending transversely of the 35 flow of fuel through the conduit and coinciding substantially with the plane of the front face of said jet head, said deflector vane being arranged with no part of its extended axis passing into the upwardly directed portion of said riser 40 conduit.

2. In a furnace having a wall with a firing opening therein, a stoker for feeding fuel to said furnace comprising a riser conduit having an upwardly extending portion and a forwardly 45 directed discharge mouth in communication with said firing opening, means below the level of said discharge mouth for urging fuel upwardly through said riser conduit in a core shaped mass, distributing means at the discharge mouth of said 50 riser conduit including a distributor plate and a distributor jet head at the rear of said distributor plate, said jet head having a front face provided with a plurality of jet openings for emitting blasts of pressure fluid over said distributor plate, and a fuel deflector vane associated with said distributing means and arranged to act on the fuel prior to the action thereon of the pressure fluid blasts issuing from said jet head, said deflector vane including an upright 55 forward edge disposed mainly in the vertical plane of the front face of said jet head and including a lower portion extending a slight distance forwardly of said front face, said deflector vane being pivotally mounted at substantially 60 its forward end for movement about an upright axis, said vane being disposed in said conduit with its pivotal axis lying in a plane extending transversely of the flow of fuel through the 65 conduit and coinciding substantially with the plane of the front face of said jet head, said deflector vane being arranged with no part of its extended axis passing into the upwardly directed portion of said riser conduit.

3. In a furnace having a wall with a firing opening therein, a stoker for feeding fuel to said furnace comprising a riser conduit having an upwardly extending portion and a forwardly directed discharge mouth in communication with said firing opening, means below the level of said discharge mouth for urging fuel upwardly through said riser conduit in a core shaped mass, distributing means at the discharge mouth of said 5 riser conduit including a distributor plate and a distributor jet head at the rear of said distributor plate, said jet head having a front face provided with a plurality of jet openings for emitting blasts of pressure fluid over said distributor plate, and 10 a fuel deflector vane associated with said distributing means and arranged to act on the fuel prior to the action thereon of the pressure fluid blasts issuing from said jet head, said deflector vane including an upright forward edge disposed 15 mainly in the vertical plane of the front face of 20 said jet head and including a lower portion having an enlarged forward end extending a slight distance forwardly of said front face, said deflector vane being pivotally mounted at substantially its 25 forward end for movement about an upright axis, said vane being disposed in said conduit with its 30 pivotal axis lying in a plane extending transversely of the flow of fuel through the conduit and coinciding substantially with the plane of the front face of said jet head, said deflector vane being arranged with no part of its extended axis passing into the upwardly directed portion of said riser conduit.

4. In a furnace having a wall with a firing

opening therein, a stoker for feeding fuel to said furnace comprising a riser conduit having an upwardly extending portion and a forwardly directed discharge mouth in communication with said firing opening, means below the level of said discharge mouth for urging fuel upwardly through said riser conduit in a core shaped mass, distributing means at the discharge mouth of said riser conduit including a distributor plate and a distributor jet head at the rear of said distributor plate, said jet head having a front face provided with a plurality of jet openings for emitting blasts of pressure fluid over said distributor plate, and a fuel deflector vane associated with said distributing means and arranged to act on the fuel prior to the action thereon of the pressure fluid blasts issuing from said jet head, said deflector vane including an upright forward edge the lower portion of which is enlarged and extends a slight distance forward of the front face of said jet head and the upper portion of which forward edge is disposed rearward of the lower portion, said deflector vane being pivotally mounted at substantially its forward end for movement about an upright axis, said vane being disposed in said conduit with its pivotal axis lying in a plane extending transversely of the flow of fuel through the conduit and coinciding substantially with the plane of the front face of said jet head, said deflector vane being arranged with no part of its extended axis passing into the upwardly directed portion of said riser conduit.

GEORGE M. BROKER.
